JOHN W. MARSH, OF NEW YORK, N. Y.

SWING-TRUCK-YOKE SUPPORT FOR RAILROAD ROLLING-STOCK.

1,388,818.

Specification of Letters Patent. Patented Aug. 23, 1921.

Application filed November 7, 1919. Serial No. 336,317.

To all whom it may concern:

Be it known that I, JOHN W. MARSH, a subject of George V, King of Great Britain and Ireland, and a resident of the city of 5 New York, borough of Manhattan, county and State of New York, have invented a new and Improved Swing-Truck-Yoke Support for Railroad Rolling-Stock, of which the following is a full, clear, and exact description.

This invention relates to trucks for railroad rolling stock, and more particularly to improvements in the axle box construction and supporting means for carrying the 15 weight of the car or locomotive upon the axle box and car wheels.

An object of the invention is to provide an improved base or supporting means for supporting a yoke used in truck construction, and particularly locomotive trucks. It is a purpose to effectively enable and promote the practice of a kindred invention, as shown in a joint application filed in the United States Patent Office on the 25th day 25 of August, 1919, A. D. under the Serial No. 319,620.

In the kindred application filed as above stated, the inventors thereof have disclosed a new and improved type of radial truck 30 for use in connection with railroad rolling stock, and particularly for use in connection with large heavy locomotives of long wheel base. It becomes the part and purpose of the presently described invention to provide 35 a valuable and useful structure preferably employed as an element or sub-combination in constructing a radial truck in accordance with the kindred invention.

In presenting this invention I have particularly in view the provision of new and improved means for accommodating a swinging yoke employed as an element in the above identified kindred invention, and to provide a means by which the swingingly 40 mounted yoke and supporting axle box may undergo adequate relative movements one with the other in the several directions of motion to which the yoke and axle box are subject when moving along a railroad track.

50 It is a particular object of this invention to provide a specially designed axle box to accommodate a slide, and to support a truck yoke upon the slide to permit the yoke to undergo the required movements relatively

to the axle box. In mounting a yoke over 55 an axle box it is necessary to provide for the sliding, twisting, and rocking action which the yoke undergoes relatively to the axle box, and this invention is conceived to accomplish these ends.

In constructing large and powerful steam or electrical locomotives it is necessary to extend the length of the locomotive and in doing this the builder must provide adequate trucks for guiding the drivers around 60 curves. In order to build locomotive trucks of sufficient capacity with means to accommodate the increased side swing and travel of the locomotive frame over the truck, it becomes necessary to employ a radial truck 65 which may be similar to the one disclosed in the kindred application, and to provide a yoke mount or support, as herein disclosed, to complete the structure of the radial truck, and render more competent the function of 70 the radial truck.

With the above principal objects in view and others, the invention has relation to a certain combination and arrangement of parts, several designs and modifications 80 thereof being presented in the several appended claims, and one practical working design of which is described in this specification, and portrayed in the accompanying drawings, wherein:

85 Figure 1 shows a combination side elevation and sectional view of the flexible or swinging yoke carried upon an axle box.

Fig. 2 shows an end elevation thereof with the yoke and associate parts in section, and 90 with the axle box and a truck wheel in elevation. This view shows the yoke hanging in normal position as when the truck is traveling on a straight track.

Fig. 3 illustrates the same parts as Fig. 2, 95 however the position of the yoke is swung over to one side which shows the action as the truck rounds a curve.

Fig. 4 illustrates a plan view of the axle box with parts of the yoke mount or support 100 placed in position within the channeled recess of the axle box. The parts confined in the channeled recess of the axle box are shown with parts thereof broken away to expose a top view of one of the ribs used on 105 a certain rocker base employed to support the yoke.

Figs. 5 and 6 illustrate an underneath per-

spective view and a top perspective view of a certain rocker employed in connection with the swingingly mounted yoke and axle box. This part is termed the rocker in the invention.

Fig. 7 presents a perspective view of the underneath side of a rocker base which supports the above mentioned rocker.

Fig. 8 shows a top perspective view of a slide which is carried by the axle box and in turn supports the aforesaid rocker base.

Fig. 9 illustrates a top perspective view of a specially designed axle box, disclosing the channeled recess formed therein to receive the aforesaid slide.

Fig. 10 shows another combination side elevation and sectional view in order to illustrate the use of a modified form of yoke supporting base.

Fig. 11 shows a yoke in section to disclose the interior shape and design.

Figs. 12 and 13 show perspective views of modified yoke supporting elements.

This specification and accompanying drawings are directed to one yoke and axle box assembly. It is understood however that a completed device would consist of a duplication of the apparatus shown in the drawings, that is to say, would consist of a yoke mounted over each axle box on the outside of each truck wheel. The yokes would then be joined together by the usual equalizer bars.

In constructing a swing truck yoke support for railroad rolling stock in accordance with my invention, it is necessary to provide an axle box having all the characteristics of the well known present type, but specially designed on the upper face thereof to retain a rocker base. And in order to accommodate the sliding and twisting motion which the axle box undergoes relatively to the rocker base, it may be necessary to employ a slide interposed between the rocker base and the axle box. A spring support is next mounted on the rocker base, said spring support being herein called a rocker. The rocker holds a spring, and a yoke is hung on the spring. The device is then assembled and used in connection with a radial truck to suit the needs of the railroad requirements as set forth in the above identified kindred invention.

In further describing my invention, reference is made to the accompanying drawings wherein the various parts are particularly pointed out by reference characters. A description is first given of the important parts of the invention, and their construction. The support device will then be described in connection with the axle box to complete the understanding of its use and operation.

Referring to Fig. 8, a slide 10 is provided and has upstanding parallel ribs which form a wide channel to receive a rocker base.

The slide is rectangular in shape to fit into a channeled guide of an axle box as later seen. The ribs are not essential, but may be used to advantage to obtain a greater bearing area to transfer side thrust of the truck to the axle box. The slide is centrally bored or turned to form a socket bearing 12.

Fig. 7 discloses a rocker base consisting of a flat plate 14 with a number of parallel upstanding ribs 15. A cylindrical boss 16 is formed on the under plane surface of this rocker base. The boss 16 works in the socket bearing 12 to center the rocker base 14 in proper relation with the slide 10, and to permit said slide to undergo a slight twisting or rotary motion under the rocker base 14. The opposite sides or edges 17 are straight and relieved from the center back to the corners in plan as shown in Figs. 4 and 7. By referring to Fig. 4, which is a plan view, it is more clearly seen how the oppositely straight but relieved edges 17 permit the slide to undergo a limited twisting motion under the rocker base.

Figs. 5 and 6 of the drawings illustrate a rocker which is carried by the rocker base 14. This rocker is made with upstanding parallel sides 19 integrally formed with a horizontal base 20, and on each end of the base is integrally formed substantial heavy depending lips 21. On the upper face of the base 20 is formed a channel 33 extending down the parallel sides and across the base. The channel in the base proper is obtained by leaving ribs extending parallel across the base 20. This channel 33 functions as a seat to properly align and retain the spring and yoke in position as later seen. On the underneath side of the base 20 are formed parallel grooves or seats 22 having a surface configuration about equal to the surface configuration of the upstanding ribs 15 of the rocker base. The rocker is placed in position on the base 14 with the ribs 15 fitting into the grooves 22. This disposes the lips 21 over the end edges of the rocker base and holds the rocker and rocker base together in a joint relationship, but allows the rocker to tilt back and forth over the rocker base resting first upon one rib 15 and then the other. By observing Fig. 1 the lip is shown to overhang the end edge of the rocker base in full lines, and by observing Figs. 2 and 3 the same position is seen in dotted lines. In this manner the base 14 is confined under the rocker.

Reference is now made to the assembly views of the drawing where a truck yoke 27 is employed, and which is built in the form of a channel which spaces apart its vertical walls, and as later seen, the parts associated with the yoke are inserted between the walls of the channel in the upper portion of the yoke. In the central part of the yoke, a portion of the web is removed to leave an

open space into which is inserted the rocker 20 and its associated parts. Lips 39 are integrally formed with the web of the yoke, and terminate the web to leave the aforesaid opening. The rocker is confined in this opening and the lips 39 contact the rocker to restrain said rocker from longitudinal movement but to permit vertical movement. Above the opening in the yoke there is another web 40 formed integrally with the walls of the yoke to truss and strengthen said yoke. The yoke 27 has downwardly diverging arms, and on the lower ends thereof are provided suitable coupling pins 15 for joining it with truck equalizer bars in case equalizers are employed, or in case it is directly connected, to the frame of the rolling stock.

A truck spring 24 is bound with a band 20 25 to join together the plurality of plate springs to form a spring assembly. The spring is seated in the rocker by disposing the binder band 25 in the spring seat 33 of the rocker 20. A hanger 26 is suspended on 25 each end of the spring, and a pin 28 is inserted through the lower end of each hanger and through the walls of the yoke to suspend the yoke 27 on the spring 24. The spring therefor supports the truck yoke in 30 a manner as disclosed in the drawings. Adequate clearance is provided between the yoke and the axle box to allow vertical movement of the yoke due to its spring suspension. In case the spring should break, 35 the yoke 27 immediately drops down on the spring with the web 40 resting against the spring band 25. In this position the truck yoke and associated parts will continue to function even though the spring fails.

The axle box 29 employed in connection with this axle and truck yoke mount may have the same journal and bearing design as is characteristic with present type axle boxes, but the top side thereof is finished to 45 form a horizontal plane slide surface in the form of a guide or channel 30, with adjacent upstanding parallel ribs 31. The channel or guide 30 slidably supports the slide 10 which is disposed in the channel with the rocker base mounted on and within the slide. Fig. 4 discloses in plan the axle box with the slide, rocker base, and rocker in assembly. A half portion of the rocker is broken away to expose one of the ribs of the rocker 50 base. The axle box is made with a hollow opening horizontally formed therethrough to receive a bar to join all parts in a transient relationship.

In order to lift and transport the truck 60 to or from the track, a lift bar 38 is inserted through the opening in the axle box and has each end fixed to the yoke. This joins the yoke and axle box together and prevents the yoke from becoming disengaged 65 from the axle box. The lift bar is neces-

sarily employed to hold the truck assembly together when being lifted from and replaced on railroad tracks by a crane.

An oil sump 32 may be formed in the axle box, and in the present design it is found 70 convenient to provide this sump within one of the walls or in the rib of the axle box. Any suitable means of transmitting oil from the sump to the bearing faces of the working parts may be employed such as drilling holes 75 to communicate the sump with the working faces of the axle box, slide, and rocker base, and inserting oil wicks or other means therein.

The axle box is fixedly mounted on the 80 frame 34 and journals the truck axle 35 which carries the truck wheel 36. Truck equalizer bars 37 are connected with each yoke arm, and these equalizer bars couple up with the locomotive frame and springs to 85 transmit a portion of the load from the locomotive frame to the truck yokes, through the rocker, rocker base, and slide onto the axle box and thence to the wheel.

In the operation of this truck yoke support, the yoke 27 hangs vertically while the truck travels on a straight track. However, when the truck rounds a curve the frame of the locomotive draws the equalizers transversely across the track due to the wheels 90 following the curve while the engine frame points off at a tangent. This action swings the truck yoke 27 to one side as shown in Fig. 3 and causes the rocker 20 to ride upon one of the rocker base ribs 15. Simultaneously with this swinging action of the yoke, the axle box 29 undergoes a sliding motion under the slide 10, the associated 95 rocker base 14 and other parts. The rocker is held longitudinally with the yoke 27 and 100 connected locomotive frame by the upturned lips 39 terminating the upper part of the wall which comprises the web of the truck yoke section. The rocker base and slide are held together by engagement of the socket 105 bearing 12 and base 16, while the rocker and rocker base are held together by the lips 21 of the rocker, as the axle box moves under the slide. Simultaneously with this last 110 described movement there occurs a slight rotary or twisting motion of the rocker base relatively with the slide. The twisting motion is due to the radial travel of the axle box and slide which causes the slide to rotate slightly under the rocker base. In this 115 manner the several different relative motions occurring between the yoke and the axle box are adequately accommodated by the interposed slide 10, rocker base 14, and rocker 20.

When the yoke swings over the axle box 120 and rides upon one of the ribs 15, there are developed certain forces which act to draw the locomotive frame around the curve. As long as the yoke hangs in a vertical position the forces are neutral, but when the yoke 125

swings to one side or the other, the eccentricity of the mounting of the single supporting rib acts to forcibly draw the locomotive frame around the curve and off the tangent which it tends to travel.

The load of the locomotive imposed on each truck wheel 36 is rested upon the ribs 15 which acts to stabilize the locomotive over the truck when traveling on a straight track. 10 This reduces side swing to a minimum and results in a smooth easy riding locomotive free from lateral sway.

The Figs. 12 and 13 disclose another type of slide 50 and rocker base 52. The slide 15 comprises a flat plate with a bearing hole 51 formed through the body thereof to receive the circular base 52. The base 52 projects through the slide 50 and rests directly on the axle box while the slide 50 functions as 20 a guide or retainer to hold the rocker base 52 in position, and further to transmit the side thrust acting through the apparatus to draw the drivers around a curve as more particularly brought out in the kindred application. The base 52 carries the supporting ribs 15 the same as previously described.

The invention is presented to fill the want felt for a truck yoke support to facilitate the construction and use of the radial truck 30 disclosed in the kindred invention in order to promote generally the erection of large and heavy locomotives of long wheel base.

Having thus described my invention, what I claim as new and desire to secure by Letters Patent is:

1. A support bed to mount a truck yoke over an axle box, comprising: a pair of relatively movable members interposed between the truck yoke and the axle box to permit 40 the truck yoke to undergo a swingingly transverse motion, and to permit the axle box to travel longitudinally relative to the yoke.

2. A swing truck yoke support for railroad rolling stock, to mount the yoke over an axle box, comprising in combination: a pair of relatively movable members interposed between the truck yoke and the axle box to permit the truck yoke to undergo a 50 swingingly transverse motion, and to afford said truck yoke a simultaneous longitudinal travel relatively to the axle box.

3. A mounting means to carry a truck yoke over a railroad axle box, comprising: a 55 rocker associated with the yoke, a slide associated with the axle box, and a rocker base interposed between the slide and the rocker.

4. A swing truck yoke support for railroad rolling stock, in combination with an 60 axle box; an axle box provided with an upper plane grooved surface, a device slidably confined on the plane grooved surface, and a yoke supported by the device.

5. A swing truck yoke support for rail-

road rolling stock, in combination with an 65 axle box; an axle box provided with a guideway, device slidably confined in the guideway, a yoke mounted on the device for the purpose of permitting relative motion between the yoke and the axle box. 70

6. A swing truck box support for railroad rolling stock, in combination with an axle box, comprising: an axle box having receptive means to support a device, a device adapted to be so supported, ribs formed on 75 the device, and a yoke resting in contact with the ribs.

7. A swing truck yoke support for railroad rolling stock, in combination with an axle box, a member carried by the axle box, 80 ribs formed on the member, a yoke carrying a member resting in contact with the ribs to permit a transverse rocking motion of the yoke relatively to the axle box, and means provided to permit the axle box to travel longitudinally relatively to the yoke. 85

8. A swing truck yoke support for railroad rolling stock, in combination with an axle box, a member carried by the axle box, 90 projections formed on the member, a yoke carrying a member resting in contact with the projections, whereby said yoke is capable of a transverse rocking motion over the axle box, and means for restraining the yoke against longitudinal movement while the 95 axle box undergoes longitudinal motion.

9. A swing truck yoke support for railroad rolling stock, in combination with an axle box; an axle box provided with a receptacle, a member confined in the receptacle and held stationary while the axle box moves relatively to the member, a device related with the member in such a manner as to rock or tilt in one direction but restrained from motion in other directions 100 relative to the member, and a yoke carried upon the device. 105

10. A swing truck yoke support for railroad rolling stock, in combination with an axle box; an axle box provided with a guideway, a member confined in the guideway and held stationary while the axle box moves relatively to the member, a device related with the member in such a manner as to rock or tilt thereon but restrained from motion 110 relatively right angular to the rocking motion of the device, a yoke carried upon the device, and a spring support interposed between the device and the yoke in order to support the yoke upon the device. 115

11. A swing truck yoke support for railroad rolling stock, in combination with an axle box: an axle box provided with a guideway, a member confined in the guideway and held stationary while the axle box moves 120 relatively to the member, a device related with the member in such a manner as to rock or tilt in one direction but restrained from 125

motion in other directions relative to the member, a yoke carried upon the device, a spring support interposed between the device and the yoke in order to support the

5 yoke upon the device, and a means to retain the yoke, axle box, and other parts in assembly when the truck is lifted from a track.

12. A swing truck yoke support for railroad rolling stock, in combination with an 10 axle box, comprising: a slide mounted on an axle box, a rocker base mounted on the slide, a rocker mounted upon the rocker base, and a yoke mounted on the rocker.

13. A swing truck yoke support for railroad rolling stock, in combination with an 15 axle box, comprising: a slide carried on an axle box, a rocker associated with the slide to tilt back and forth thereupon but restrained from motion right angular to the 20 tilting motion, and a yoke carried by the rocker.

14. A swing truck yoke support for railroad rolling stock, in combination with an 25 axle box, comprising: a slide carried by an axle box, a rocker associated with the slide to tilt back and forth thereupon but restrained from a motion transverse to the tilting motion, a yoke carried on the rocker, and a spring suspension means interposed between the rocker and the yoke to resiliently 30 support the yoke upon the rocker and over the axle box.

15. A swing truck yoke support for railroad rolling stock, in combination with an 35 axle box, comprising: a slide, a rocker base mounted on the slide and capable of motion relative thereto, a rocker mounted on the rocker base and capable of motion relatively to the rocker base, and a yoke carried upon 40 the rocker.

16. A swing truck yoke support in combination with a railroad axle box, comprising: a slide carried on a railroad axle box, a 45 rocker base associated with the slide, a rocker associated with the two aforesaid elements, a spring mounted on the rocker, and a yoke supported by the spring.

17. A swing truck yoke support, in combination with a railroad axle box, comprising: a slide carried on a railroad axle box, a rocker base associated with the slide, a rocker associated with the two aforesaid elements, a spring mounted on the rocker, a yoke supported by the spring, and means 55 provided for holding the aforesaid parts together when the truck is lifted from the track.

18. A swing truck yoke support, in combination with a railroad axle box, comprising: a slide carried on a railroad axle box, a 60 rocker base associated with the slide, a rocker associated with the two aforesaid elements, a spring mounted on the rocker, a yoke supported by the spring, and a lift

bar fixed to the yoke and associated with the 65 axle box to hold the axle box and yoke together when the truck is lifted from a track.

19. A swing truck yoke support, in combination with an axle box, comprising: a slide carried upon an axle box, upstanding 70 projections integral with the slide, a rocker member tiltingly supported on the projections, a spring supported upon the rocker member, and a truck yoke suspended on the spring. 75

20. A swing truck yoke support for railroad rolling stock, in combination with an axle box, comprising: a slide carried upon an axle box, a rocker associated with the slide, means interposed between the rocker 80 and the slide to permit the rocker to undergo a tilting motion relatively to the slide, and means provided to restrain the slide and rocker from relative motion in a direction approximately right-angular to the tilting 85 plane of the rocker.

21. A swing truck yoke construction for use in combination with a railroad axle box; a yoke cast in channel form with a web and upstanding spaced parallel walls, ears terminating the web to leave an opening, and means inserted in the opening of the web to swingingly support the yoke over an axle 90 box.

22. A truck yoke construction for use in 95 combination with a railroad axle box; a yoke cast in channel form with a web and upstanding spaced parallel walls, ears terminating the web to leave an opening, and means inserted in the opening of the web to 100 support the yoke over an axle box.

23. A truck yoke construction for use in combination with a railroad axle box; a yoke cast in channel form with a web and upstanding spaced parallel walls, ears terminating the web to leave an opening, means inserted in the opening of the web to support the yoke over an axle box, and means for permitting the axle box to move relatively 105 to the yoke. 110

24. A swing truck yoke construction for use in combination with a railroad axle box; a yoke cast in channel form with a web and walls, said web having an opening formed therein centrally to the yoke, a web integrally formed with the walls of the yoke above the opening, a spring inserted between the walls of the yoke and above the opening, means for connecting the spring and the yoke, a device to support the spring, 115 said device vertically movably mounted in the opening of the yoke, and a base upon which is carried the device with its related 120 spring and yoke.

25. A swing truck yoke construction in 125 combination with an axle box; a hollow yoke with an opening formed therein, a rocker mounted in the opening of the yoke,

a spring carried upon the rocker and acting to support the hollow yoke, and a web forming an integral part of the hollow yoke disposed above the spring to catch the yoke in case the spring breaks and releases its supporting hold on said yoke.

26. A base or supporting means for carrying a swing yoke on a vehicle carriage, comprising: a slide provided with a socket bearing, a rocker base, a boss formed on the rocker base to fit into the socket bearing of the slide, projections formed on the rocker base, and a rocker mounted upon the projections of the rocker base.

10 27. A base or supporting means for carrying a swing yoke on a vehicle carriage, comprising: a slide provided with a socket bearing, a rocker base, a boss formed on the rocker base to fit into the socket bearing of the slide, ribs formed on the rocker base, and a rocker mounted upon the ribs of the rocker base.

25 28. A base or supporting means for carrying a swing yoke on a vehicle carriage, comprising: a slide having a socket bearing, upstanding ribs integrally made with the slide, a rocker base having arcuate edges and carried on the slide, a bearing boss integrally formed with the rocker base and fitting into the socket bearing of the slide in such a manner as to place the upstanding ribs of the slide tangent to the arcuate edges of the rocker base, ribs formed on the rocker base, and a rocker mounted on the ribs of the 35 rocker base.

30 29. A base or supporting means for carrying a swing yoke on a vehicle carriage, comprising: a slide having a socket bearing, a rocker base, a boss integral with the rocker base and fitting into the socket bearing of the slide, ribs formed on the rocker base, and a rocker provided with grooves or seats having a surface configuration about equal to the surface configuration of the ribs of the 45 rocker base in order that the rocker may tilt upon the ribs of the rocker base.

35 30. A base or supporting means for carrying a swing yoke on a vehicle carriage, comprising: a slide having a socket bearing, a rocker base, a boss integral with the rocker base and fitting into the socket bearing of the slide, ribs formed on the rocker base, and a rocker provided with grooves or seats having a surface configuration about equal to the surface configuration of the ribs of the 50 rocker base in order that the rocker may tilt upon the ribs of the rocker base, and lips formed on the rocker depending over the edge of the rocker base to hold the rocker and 60 rocker base in related position.

31. A base or supporting means for carrying a swing yoke on a vehicle carriage comprising: a slide having a socket bearing, a base, a bearing boss integral with the base and fitting in the socket bearing, a rocker,

and ribs or projections formed on either the rocker or the base and interposed between the base and the rocker to permit the rocker to undergo a tilting motion transversely of the base.

70 32. A base or supporting means for carrying a swing yoke on a vehicle carriage comprising: a slide having a socket bearing, a base, a bearing boss integral with the base and fitting in the socket bearing, a rocker, ribs or projections formed on either the rocker or the base and interposed between the base and the rocker to permit the rocker to undergo a tilting motion transversely of the base, and lips depending from the rocker overhanging the base to lock the rocker and base in related position.

75 33. A base or supporting means for carrying a swing yoke on a vehicle carriage comprising: a slide, a rocker base means interposed between the slide and rocker base to join them together permitting relative concentric movement by restraining them against longitudinal movement, a rocker mounted upon the base, means interposed between the rocker and the base to permit a relative tilting motion between the rocker and said base but to restrain the rocker and the base from relative longitudinal movement.

80 34. A base or supporting means for carrying a swing truck yoke used in connection with railroad rolling stock, comprising: an axle box provided with a slide surface, a rocker base supported on the slide surface, and a rocker mounted on the rocker base.

85 35. A base or supporting means for carrying a swing truck yoke used in connection with railroad rolling stock, comprising: an axle box provided with a slide surface, a 105 rocker base supported on the slide surface, a rocker mounted on the rocker base, and ribs interposed between the rocker and the rocker base.

90 36. A base or supporting means for carrying a swing truck yoke used in connection with railroad rolling stock, comprising: an axle box having upstanding ribs to form a slide surface, a rocker base mounted on the axle box and on the slide surface, a slide associated with the axle box and the rocker base to hold the rocker base in proper relation with the axle box, and a rocker swingingly carried upon the rocker base.

95 37. A base or supporting means for carrying a swing truck yoke used in connection with railroad rolling stock, comprising: an axle box having upstanding ribs to form a slide surface, a rocker base mounted on the axle box and on the slide surface, a slide associated with the axle box and the rocker base to hold the rocker base in proper relation with the axle box, a rocker swingingly carried upon the rocker base, and ribs or projections interposed between the rocker 120 and the base.

and the rocker base for the purpose of facilitating the swinging movement of the rocker.

38. A base or supporting means for carrying a swing truck yoke used in connection with railroad rolling stock, comprising: an axle box specially designed to form a slide surface thereon, a rocker base mounted on the slide surface of the axle box, a boss integrally formed with the rocker base, a slide having a hole bored therein fitting around the boss of the rocker base, and a rocker mounted upon the rocker base.

39. A base or supporting means for carrying a swing truck yoke over an axle box, comprising: a rocker base adapted to fit into a recess formed in an axle box and rest upon said axle box, upstanding ribs or projections integral with the rocker base, and a rocker carried by the yoke and swingingly carried upon the rocker base.

40. A base or supporting means for carrying a swing truck yoke over an axle box, comprising: a rocker base resting in position upon an axle box, a slide associated with the rocker base and axle box to maintain the rocker base in correct position upon the axle box, and a rocker mounted on the rocker base.

41. A base or supporting means for carrying a swing truck yoke used in connection with railroad rolling stock, comprising: an axle box provided with a slide surface, a rocker base supported on the slide surface, a rocker mounted on the rocker base, a spring supported on the rocker, and a truck yoke hung upon the spring to swing over the axle box.

42. A base or supporting means for carrying a swing truck yoke used in connection with railroad rolling stock, comprising: an axle box provided with a slide surface, a rocker base supported on the slide surface, a rocker mounted on the rocker base, ribs on the rocker or the rocker base between the rocker and the rocker base, a spring supported on the rocker, and a truck yoke hung upon the spring to swing over the axle box upon the ribs.

43. A base or supporting means for carrying a swing truck yoke used in connection with railroad rolling stock, comprising: an axle box having upstanding ribs to form a slide surface, a rocker base mounted on the axle box and on the slide surface, a slide associated with the axle box and the rocker base to hold the rocker base in proper relation with the axle box, a rocker swingingly carried upon the rocker base, a spring supported on the rocker, and a truck yoke hung upon the spring to swing over the axle box.

44. A base or supporting means for carrying a swing truck yoke used in connection with railroad rolling stock, comprising: an axle box having upstanding ribs to form a

slide surface, a rocker base mounted on the axle box and on the slide surface, a slide associated with the axle box and the rocker base to hold the rocker base in proper relation with the axle box, a rocker swingingly carried upon the rocker base, ribs or projections interposed between the rocker and the rocker base for the purpose of facilitating the swinging movement of the rocker, a spring supported on the rocker, and a truck yoke hung upon the spring to swing over the axle box.

45. A base or supporting means for carrying a swing truck yoke used in connection with railroad rolling stock, comprising: an axle box specially designed to form a slide surface thereon, a rocker base mounted on the slide surface of the axle box, a boss integrally formed with the rocker base, a slide having a hole bored therein fitting around the boss of the rocker base, a rocker mounted upon the rocker base, a spring supported on the rocker, and a truck yoke hung upon the spring to swing over the axle box.

46. A base or supporting means for carrying a swing truck yoke over an axle box, comprising: a rocker base adapted to fit into a recess formed in an axle box and rest upon said axle box, upstanding ribs or projections integral with the rocker base, a rocker swingingly carried upon the rocker base, a spring supported on the rocker, and a truck yoke hung upon the spring to swing over the axle box.

47. A base or supporting means for carrying a swing truck yoke over an axle box, comprising: a rocker base resting in position upon an axle box, a slide associated with the rocker base and axle box to maintain the rocker base in correct position upon the axle box, a rocker mounted on the rocker base, a spring supported on the rocker, and a truck yoke hung upon the spring to swing over the axle box.

48. A yoke in combination with an axle box: a yoke member cast hollow and mounted over an axle box, a spring inserted within the hollow yoke and resting on the axle box, and a web forming an integral part of the yoke over the spring to support the yoke upon the spring in case the spring fails.

49. Improvements in axle box construction and supporting devices for railroad trucks, comprising an axle box to receive and journal the truck wheel and axle set, a yoke disposed over the axle box, ribs interposed between the yoke and axle box, and said devices provided with grooves in which the ribs rest.

50. In combination with an axle box, of a yoke mounted thereon, of means for allowing the yoke to undergo a swinging motion, and a spring resting on the axle box and supporting the swinging yoke.

51. An appliance for railroad rolling stock

- comprising in combination, an axle box, a spring resting on the axle box, and a yoke carried by the spring so the yoke and spring may swing over the axle box.
5. An appliance for railroad rolling stock comprising in combination, an axle box having a recess formed therethrough, suitable supporting means mounted on the axle box for receiving the weight of a load imposed thereupon, and a device inserted through the recess in the axle box to prevent separation of the suitable supporting means from the axle box when being lifted from the track.
10. A base or supporting means for carrying a swing yoke on an axle box comprising, a rocker provided with projections formed thereon, a rocker base provided with grooves or seats to receive the projections of the rocker to allow the rocker to tilt on the projections, and means provided to permit the rocker and the rocker base to slide and twist relative to the axle box upon which they are mounted.
15. A base or supporting means for mounting a spring over an axle box comprising, a rocker, a spring mounted on the rocker, a rocker base arranged to support the rocker, and projections interposed between the rocker and the rocker base to permit the rocker and spring to tilt upon the rocker base.
20. An appliance for railroad rolling stock
- comprising in combination, an axle box, a yoke mounted over the axle box, a base interposed between the yoke and the axle box to permit adequate lateral and longitudinal motion between the axle box and the yoke, said axle box provided with a reservoir to contain lubricant, and means related with the axle box for lubricating the parts.
25. An appliance for railroad rolling stock comprising in combination, an axle box having a recess formed therein, supporting means mounted on the axle box for receiving a load imposed thereupon, and a bar extending through the recess formed in the axle box to prevent separation of the supporting means from the axle box and having its ends secured to the supporting means when being lifted from the track.
30. An appliance for railroad rolling stock comprising in combination, an axle box, a rocker base carried on the axle box and adapted to undergo relative motion thereto, a rocker mounted upon the rocker base and adapted to undergo a tilting motion thereupon, the said rocker base and rocker being provided with ribs and grooves arranged to register one in the other to permit the aforesaid tilting motion, and supporting means carried by the rocker to receive the load imposed on the axle box.
35. An appliance for railroad rolling stock comprising in combination, an axle box, a base interposed between the yoke and the axle box to permit adequate lateral and longitudinal motion between the axle box and the yoke, said axle box provided with a reservoir to contain lubricant, and means related with the axle box for lubricating the parts.
40. An appliance for railroad rolling stock comprising in combination, an axle box having a recess formed therein, supporting means mounted on the axle box for receiving a load imposed thereupon, and a bar extending through the recess formed in the axle box to prevent separation of the supporting means from the axle box and having its ends secured to the supporting means when being lifted from the track.
45. An appliance for railroad rolling stock comprising in combination, an axle box, a rocker base carried on the axle box and adapted to undergo relative motion thereto, a rocker mounted upon the rocker base and adapted to undergo a tilting motion thereupon, the said rocker base and rocker being provided with ribs and grooves arranged to register one in the other to permit the aforesaid tilting motion, and supporting means carried by the rocker to receive the load imposed on the axle box.
50. An appliance for railroad rolling stock comprising in combination, an axle box, a base interposed between the yoke and the axle box to permit adequate lateral and longitudinal motion between the axle box and the yoke, said axle box provided with a reservoir to contain lubricant, and means related with the axle box for lubricating the parts.
55. An appliance for railroad rolling stock comprising in combination, an axle box, a base interposed between the yoke and the axle box to permit adequate lateral and longitudinal motion between the axle box and the yoke, said axle box provided with a reservoir to contain lubricant, and means related with the axle box for lubricating the parts.
60. An appliance for railroad rolling stock comprising in combination, an axle box, a base interposed between the yoke and the axle box to permit adequate lateral and longitudinal motion between the axle box and the yoke, said axle box provided with a reservoir to contain lubricant, and means related with the axle box for lubricating the parts.

JOHN W. MARSH.
